UNITED STATES PATENT OFFICE.

ERNST THEODOR EDLUND, OF NEW YORK, N. Y.

BEDCLOTHES-HOLDER.

1,371,880.

Specification of Letters Patent. Patented Mar. 15, 1921.

Application filed October 14, 1920. Serial No. 416,928.

To all whom it may concern:

Be it known that I, ERNST THEODOR EDLUND, a subject of the King of Sweden, and a resident of the city of New York, borough 5 of Manhattan, in the county and State of New York, have invented a new and Improved Bedclothes-Holder, of which the following is a full, clear, and exact description.

10 My invention relates to a device for securing bed clothes on a bed to prevent their being accidentally displaced; the invention being more particularly intended for use on children's beds.

15 The general object of the invention is to provide a device for the indicated purpose adapted to be disposed across the bed at the foot providing means for engaging the bed clothes at their lower edges.

20 A more specific object of the invention is to provide the holder with means whereby the bed clothes may be quickly clamped or unclamped as well as means to utilize the mattress in maintaining the bed clothes 25 holder in position.

Reference is to be had to the accompanying drawings forming a part of this specification, it being understood that the drawings are merely illustrative of practical examples of the invention.

30 Figure 1 is a plan view of the bed clothes holder embodying my invention, part of it being broken away, the holder being shown in position ready to be positioned in the 35 bed, and the bed clothes clamp being in the open position.

Fig. 2 is a rear elevation of a bed clothes holder in folded form, the position of the swingable clamp being the same as when 40 in clamping position as in use.

Fig. 3 is a side elevation of portions of a bedstead and mattress with my improved bed clothes holder in position, the holder and the bed clothes being in section, taken 45 transversely of the holder, and longitudinally of the bed.

Fig. 4 is a fragmentary view in transverse vertical section, showing the clamping means in slightly different form.

50 In Fig. 3 the letter A indicates a portion of the bed clothes at the foot of a bed, B a fragment of a bedstead, and C a portion of a mattress.

Referring more particularly to Figs. 1 55 to 3, my improved holder comprises an elongated relatively fixed part 10 arranged to

be disposed transversely across the foot of the bed, between the lower end of the mattress and the foot of the bed. The space occupied by the holder in Fig. 3 is exaggerated in the interests of clearness. In association with elongated element 10 is an elongated element 11 adapted to coact in clamping the bed clothes at the bottom edges thereof, said element 11 preferably being 60 pivoted to swing to and from the clamping position. As here shown, the element 11 comprises a longitudinal clamp bar carried by side arms 12 pivoted at the lower ends 13 to a rearwardly projecting flange 14 70 provided on the element 10 at the lower edge thereof.

Of the elements 10, 11 the one is provided with members presenting in effect a channel, while the other is provided with a bar or 75 the like adapted to press the bed clothes into the channel. In Figs. 1 to 3 the relatively fixed element 10 is provided with a top flange 15 extending lengthwise and directed rearwardly beyond the rear face of 80 the element 10. Below the member 15 is a longitudinal rib 16, these being spaced to present a channel therebetween ranging longitudinally of the section 10, and thus ranging transversely across the foot of the 85 bed when the structure is in position for use. The swingably mounted clamp bar 11 is positioned to be swung toward the element 10 between the horizontal planes of the members 15, 16, and thereby press the bed 90 clothes A into the channel as indicated clearly in Fig. 3. In using the bed clothes holder, the bottom sheet and the top sheet, as well as the blanket and any other coverings are all brought together, bent downwardly in the rear of the holder, and then 95 pressed by the bar 11 into the channel at A.

In order to hold the clamping bar 11 in clamping position, I provide movable latches, preferably separate swingable latch elements 17 pivoted at their lower ends to a fixed part of the element 10, such for example as the rearwardly directed flange or member 14. The latches fold down alongside the member 14 to permit the clamp 11 100 to swing outwardly, and fold upwardly against said clamp when the latter is in the clamping position.

In Fig. 4 instead of the two longitudinal members such as 15 and 16 being on the relatively fixed element 10 or body of the holder, I have shown a body or relatively fixed sec-

tion 10^a having integral therewith along the top edge, a rearwardly directed flange 15^a, and the clamp 11^a I provide in the form of a channel bar presenting upper and lower flanges 11^b disposed toward the flange 15^a, which is in effect, the reverse of the arrangement in Figs. 1 to 3. The end bars 12^a of the clamp bars 11^a are pivoted as at 13^a to an integral bottom flange 14^a on the body 10^a. The same form of latches 17 are employed and pivoted at their lower ends as at 18 to flange 14^a.

In the preferred form of my invention, I provide for utilizing the mattress for preventing displacement of the holder, for which purpose I provide on the relatively fixed section 10 of the holder, forwardly extending member or members. In the illustrated example, folding bars 19 are pivoted at their rear ends 20 to the bottom of section 10, and are united at their forward ends by a cross bar 21 pivoted at their ends to said bars 19. The arrangement permits of the bars 19, 21 being folded together at the underside of the section 10, or being projected forwardly in rectangular form as in Figs. 1 and 3, whereby they may be inserted beneath the mattress C. The bars 19 may have tie strings 23 attached thereto and 30 adapted to be brought over the top of the mattress and tied.

By firmly fastening both sheets and the bed coverings together across the bottom edges, the bed clothes are securely maintained against displacement by children tossing in bed for example, and at the same time the minimum inconvenience is afforded

the children. Besides the holder when in use is completely concealed or at all events is quite inconspicuous.

I would state in conclusion that while the illustrated examples constitute practical embodiments of my invention, I do not limit myself strictly to the details herein illustrated, since manifestly the same can be considerably varied without departure from the spirit of the invention as defined in the appended claims.

I claim:

1. A bed clothes holder including an elongated body section adapted to range along the foot of a bed and having spaced elongated members thereon running substantially the length thereof, a clamp section substantially the same length as the body section and hinged to the latter to swing to and from clamping relation to said body section and having an elongated member positioned to enter the space between the members on the body, and means to hold the clamp section in clamping position.

2. A bed clothes holder comprising an elongated body section adapted to be positioned at the foot of the bed between the mattress and the bedstead, arms pivotally secured at one end to said body section, means pivotally connecting the opposite ends of said arms, said arms being adapted to be positioned beneath a mattress, and a swingable clamp section hinged at its lower edge to said body section, said body section and said clamp section having coacting members to clamp the bed clothes.

ERNST THEODOR EDLUND.
